Primary Examiner — Brian N. Vinson*(74) Attorney, Agent, or Firm* — Thrive IP®; Jeremy M. Stipkala(57) **CLAIM**

The ornamental design for a LED candle light, as shown and described.

DESCRIPTION

FIG. 1 is a perspective view of a LED candle light; FIG. 2 is a top plan view of the LED candle light of FIG. 1; FIG. 3 is a bottom plan view of the LED candle light of FIGS. 1 and 2;

FIG. 4 is a right elevation view of the LED candle light of FIGS. 1-3; and,

FIG. 5 is a left elevation view of the LED candle light of FIGS. 1-4.

The features shown in broken lines are portions of the LED candle light or are environmental subject matter that do not form part of the claimed design.

1 Claim, 4 Drawing Sheets(56)
